(57) **CLAIM**

The ornamental design for a traveling body for construction machine, or the like, as shown and described.

DESCRIPTION

FIG. 1 is a front elevational view of a traveling body for construction machine, showing our design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an enlarged sectional view taken on line A—A in FIG. 4.

FIG. 8 is a front elevational view of a second embodiment thereof;

FIG. 9 is a rear elevational view thereof;

FIG. 10 is a left side elevational view thereof;

FIG. 11 is a right side elevational view thereof;

FIG. 12 is a top plan view thereof;

FIG. 13 is a bottom plan view thereof;

FIG. 14 is an enlarged sectional view taken on line A—A in FIG. 11.

FIG. 15 is a front elevational view of a third embodiment thereof;

FIG. 16 is a rear elevational view thereof;

FIG. 17 is a left side elevational view thereof;

FIG. 18 is a right side elevational view thereof;

FIG. 19 is a top plan view thereof;

FIG. 20 is a bottom plan view thereof; and,

FIG. 21 is an enlarged sectional view taken on line A—A in FIG. 18.
